US00D939632S

(12) **United States Design Patent** (10) Patent No.: **US D939,632 S**
(45) Date of Patent: **** Dec. 28, 2021**

(54) **GAMING MACHINE**(71) Applicant: **AGS LLC**, Las Vegas, NV (US)(72) Inventors: **Rachel Calhoun Lewis**, Atlanta, GA (US); **Mark Robert Brandau**, Johns Creek, GA (US); **Sigmund Hyunjai Lee**, Atlanta, GA (US); **Kevin Lee Hohman**, North Las Vegas, NV (US); **James Ely Tillery**, Atlanta, GA (US); **Wei Gu**, Daly City, CA (US); **Ariel David Turgel**, San Francisco, CA (US); **Daniel Kendall Harden**, Palo Alto, CA (US)(73) Assignee: **AGS LLC**, Las Vegas, NV (US)(***) Term: **15 Years**(21) Appl. No.: **29/656,949**(22) Filed: **Jul. 17, 2018**(51) LOC (13) Cl. **21-03**

(52) U.S. Cl.

USPC ..... **D21/370**(58) **Field of Classification Search**

USPC D21/349, 350, 397, 329, 332, 333, 365, D21/385, 694, 371, 325, 324, 336, 369, D21/370

CPC A63F 7/027; A63F 9/00; A63F 5/04; A63F 7/02; G07F 17/321; G07F 17/3213

See application file for complete search history.

CLAIM

The ornamental design for a gaming machine, as shown and described.

DESCRIPTION

FIG. 1 is a front isometric view of a gaming machine according to a first embodiment of the present disclosure.

FIG. 2 is a front elevation view thereof.

FIG. 3 is a rear elevation view thereof.

FIG. 4 is a first side view thereof.

FIG. 5 is a second side view thereof.

FIG. 6 is a top plan view thereof.

FIG. 7 is a bottom plan view thereof.

FIG. 8 is an isometric view of a button panel and adjacent portions of the gaming machine dashboard illustrated in FIG. 1;

FIG. 9 is top plan view of the button panel illustrated in FIG. 8.

FIG. 10 is a front isometric view of a gaming machine according to a second embodiment of the present disclosure.

FIG. 11 is a front elevation view thereof.

FIG. 12 is a rear elevation view thereof.

FIG. 13 is a first side view thereof.

FIG. 14 is a second side view thereof.

FIG. 15 is a top plan view thereof.

FIG. 16 is a bottom plan view thereof.

FIG. 17 is an isometric view of a button panel and adjacent portions of the gaming machine dashboard illustrated in FIG. 10; and,

FIG. 18 is top plan view of the button panel illustrated in FIG. 17.

The shade lines in the Figures show contour and not surface ornamentation. The broken lines in the Figures show portions of the support structure and its surrounding environment that form no part of the claimed design.
